UNITED STATES PATENT OFFICE

153,306

DESIGN FOR A DISPLAY CASE

Henry L. Pearson, Langhorne, Pa., assignor to Ranger-Tennere, Inc., New York, N. Y., a corporation of New York

Application November 14, 1947, Serial No. 142,515

Term of patent 3½ years

(Cl. D80—11)

To all whom it may concern:

Be it known that I, Henry L. Pearson, a citizen of the United States, and a resident of Langhorne, in the county of Bucks and State of Pennsylvania, whose post-office address is 139 W. Maple Avenue, Langhorne, Pennsylvania, have invented a new, original, and ornamental Design for a Display Case, of which the following is a specification, reference being had to the accompanying drawing, forming part thereof.

The figure is a perspective view of a display case showing my new design.

I claim:

The ornamental design for a display case, substantially as shown.

HENRY L. PEARSON.
